GRID SUPPORT FOR FLUIDIZED SOLIDS VESSELS

Howard C. North, Westfield, N. J., assignor to Esso Research and Engineering Company, a corporation of Delaware

Application December 14, 1955, Serial No. 552,997

2 Claims. (Cl. 34—57)

This invention relates to an improved apparatus for contacting fluidized solids with gasiform fluids. The invention pertains more particularly to a vessel wherein finely divided solids, either catalytic or non-catalytic, are fluidized and treated or reacted with liquid or gaseous fluids, for example, for regenerative and/or heat production purposes at temperatures above about 900° F. This invention proposes an improved grid or gas distributor plate design for supporting, and uniformly distributing a gasiform reactant throughout, a high temperature fluidized solids bed within a reaction vessel.

This invention will find use in various fluidized solids processes such as ore roasting, drying of wet solids, coal carbonization or burning for power generation, shale retorting, catalytic cracking of gas oils, reforming of heavy naphthas, and coking of heavy oils. It has particular utility in the burning of carbon-containing solids wherein relatively high temperatures are encountered, such as in the regeneration of spent cracking or hydroforming catalyst. It is especially adapted to the partial burning of particulate fluid coke used as a heat carrier in a hydrocarbon oil fluid coking process, for supplying heated solids to the reaction zone, and will be described in relation to this fluid coking process.

In the fluid coking process, as used in the petroleum industry, a heavy oil—usually a low value residual oil, shale oil, asphalt, etc., is converted by pyrolysis to relatively lighter hydrocarbons and coke by contact with fluidized finely divided heat carrying solids maintained at a coking temperature in the range of 850° to 1600° F., or above. The coke produced by the pyrolysis deposits on the fluidized solids, layer by layer, and becomes a part thereof. The heat carrying solids normally used are coke particles produced by the process, but other types of solids can be used such as sand, spent catalyst, and metal particles.

Heat is supplied to the coking zone by withdrawing carbon containing solids from the coking zone and partially burning them as a fluidized bed in a burning zone, whereby their temperature is raised 100° to 400° F. above the coking temperature. The solids so heated are then returned to the coking zone.

This invention is concerned with an improved grid design for supporting the fluid bed within the burning zone, and for uniformly distributing the combustion air throughout the bed.

In fluidized solids vessels, it has been found desirable to provide a grid or foraminous plate to uniformly disperse the fluidizing gas or gasiform reactant throughout the bed. In early designs, this gas distributing means was placed within the bed and operated at the temperature of the bed. At high temperatures this required special alloys, usually non-weldable, to be used to resist the severe erosive and corrosive conditions. In later designs, the grid was utilized to also support the bed so that the fluidizing gas, which is usually at a lower temperature than the temperature of the bed, when passing up through the grid would cool the grid. The perforations or open-

2

ings in the grid were designed to create a pressure drop (gas velocity) over the grid sufficiently high to prevent any significant amount of the fluidized solids from passing down through the grid. By this means, it was found, for example, in the regeneration of catalyst from a gas oil catalytic cracking process, that the grid temperature could be maintained below 600° F. This permitted carbon steels to be used. Also, it became the practice to internally insulate the vessels to maintain low vessel shell temperature, e. g., about 300° to 500° F.

In the design where the grid supports the fluid bed, it was conventional practice to support the grid on a series of clips or lugs around the circumference of the vessel, the clips being welded to the shell of the vessel. The grid was bolted to the clips with the bolt holes being slotted to permit thermal movement between the grid and the relatively cool metal shell of the vessel. It was not feasible to combine the separate support clips into a continuous support ring because at high temperatures, undesirable high thermal stresses would occur, both in the ring and in the vessel shell, particularly with internally insulated vessels.

Because the clips were separate from one another, a grid sealing device has been necessary to prevent air or fluidized solids from passing through the spaces between the clips and the periphery of the grid, and also from passing through the vessel insulation. To accomplish this, a thin flexible membrane of stainless steel, welded to a vapor stop attached to the vessel shell and extending over and fastened to the grid, has been used. The grid sealing device in one design had an inverted V shape in cross section. A positive mechanical seal was thus formed which prevented any leakage around the grid or through clearances that existed in the grid support bolt holes.

35 This grid seal type of arrangement, besides being cumbersome and expensive, has proved to be somewhat unsatisfactory. It is amenable to erosion and while accommodating horizontal movement between the grid and the vessel shell, it will accommodate only very little vertical movement without rupture. Because by necessity this grid seal arrangement is thin, it will not stand a very high pressure differential over the grid, which pressure differential in fluid coke burners may be considerable.

The present invention proposes an improved grid and 45 grid sealing arrangement which overcomes these and other difficulties. This novel grid design adequately allows for differences in thermal expansion and contraction in the equipment, while providing support for the grid and preventing passage of gases around the periphery of the grid.

50 In the drawings:
Figure I illustrates a fluidized solids vessel containing a grid arrangement designed in accordance with the teachings of this invention. Figure II illustrates an alternative embodiment of this invention.

In brief compass, this invention proposes a grid in the lower portion of a fluidized solids vessel in horizontal spaced relation to the walls of the vessel, for uniformly distributing a gasiform medium throughout a fluidized bed of high temperature, particulate solids contained therein, and for supporting the bed; in combination with an in-part vertically disposed gas impervious skirt or support encompassing and connecting with the periphery of the grid, and connecting with and preferably welded to the walls of the vessel. The skirt joins the vessel walls on a plane or level vertically spaced preferably at least 18 inches from the grid. In vertical cross-section, a substantial portion of the skirt is preferably vertical, although it may be curved. At least a portion of the skirt is insulated, starting from the vessel walls.

70 Referring now to Figure I, fluidized solids vessel 1 contains a bed of fluidized particulate solids 2 having a

definite upper level 3. For purposes of illustration, the fluid bed may comprise fluid coke particles being oxidatively reheated to supply heated solids to a hydrocarbon oil fluid coking vessel. Cool solids from the fluid coking vessel are circulated and introduced into burning vessel 1 by line 4, and reheated solids at a temperature of 100° to 400° F. above the coking temperature are circulated to the coking zone via line 5, in a manner known by the art.

Air is admitted to the base of the burner vessel 1, which preferably has a cone bottom, by line 6 and fluidizes and burns the coke within the vessel to maintain a temperature therein of about 900° to 2000° F. Flue gases from the burner are vented overhead via line 7 after having entrained solids removed in cyclone system 8.

According to this invention, the fluid bed 2 is supported, and the combustion air is uniformly distributed throughout the fluid bed, by a gasiform distributing means, i. e., a perforated circular grid 9. The grid is horizontally spaced from the vessel walls, usually 1 to 3 inches, sufficient to permit thermal expansion of the grid. The grid is supported by a support and sealing means, i. e., skirt 10. This skirt is specially designed to permit thermal expansion and contraction between grid 9 and vessel 1, and to accommodate the necessary temperature differential between the vessel and grid. It is characterized by having a vertical portion or length sufficiently long to keep thermal bending stresses plus pressure stresses to an allowable value. The length and thickness of the skirt are selected depending on the specific design conditions, the actual dimensions being such that the combined pressure and bending stress is within the allowable for the material used. It is essential that the skirt have a minimum length determined by

$$\frac{dT}{dL} \sqrt{Dt}$$

where

$$\frac{dT}{dL} =$$

temperature gradient over the skirt, D =diameter of the skirt, t =thickness of the skirt, L =length of the skirt, and T =the temperature of the skirt. For most vessels, the vertical height of the skirt is at least 18 to 30 inches. To provide a reasonably smooth and low value of the temperature gradient over the skirt, it is also essential that insulation 11 within the vessel extends part way, usually 18 to 24 inches, along the skirt from the vessel walls, as shown. This reduces the bending stresses in the skirt.

Another important feature of this design is that the skirt is welded to the vessel shell, preferably with a continuous full penetration weld, to prevent passage of air and fluidized solids around the skirt. The skirt can also be welded to the grid, although other fastening arrangements can be used here.

In vessels over about 10 ft. in diameter, grid 9 is slightly dished in order to give it the membrane strength associated with curved surfaces, thus making it self-supporting and eliminating the framework of beams required to support flat grids. A downward, rather than an upward, dish is employed to reduce the volume of waste (unoccupied) space below the grid.

The amount of dish in the grid (radius of curvature) represents a compromise between mechanical and process considerations. If the radius of curvature is too small, the depth of the dish causes a significant difference in the hydrostatic head of the fluidized solids acting in the center of the grid, compared with points near its edge. This will cause a greater air flow through the edge holes and result in poor air distribution.

The grid and skirt must be designed for the most severe operating conditions expected to be encountered. This is normally a condition where the grid is called upon to

support the mass of solids in an unfluidized condition at the operating temperatures.

Figure II illustrates another embodiment of the invention wherein the grid, instead of being dependent or hanging from the skirt, is superposed on the skirt. The design of Figure I is preferred because it permits placement of the grid lower down in the vessel whereby waste space below the grid is minimized.

In Figure II, dished grid 20 is supported by a vertical continuous circular ring or skirt 21. The skirt initiates from and is welded to the cone bottom of vessel 22. As is essential, refractory lining or insulation 23 of the vessel extends part way over the skirt to create a uniform temperature differential.

It will be appreciated by those skilled in the art that this grid and grid support and seal arrangement may be used in multiple forms, thus one skirt can support two or more grids in vertical spaced arrangement, or a plurality of concentric skirts can be used to support a plurality of vertically spaced grids. It is desirable in some applications to use a plurality or series of grids to permit a wide variation in operating conditions. For example, two grids can be used with the lower one having a lesser free area or smaller perforations. In this way, with reference to a fluid coke burning vessel, when the air rate is normal, the coke bed will be supported on the upper grid having the larger openings. At low air rates or minimum capacity, when the amount of air passing through the upper grid is not sufficient to prevent coke from back-flowing through the grid, the coke bed will be supported on the lower grid having the smaller perforations or openings. To offset high pressure drops in this dual grid design, some of the air during normal operation can be admitted between the grids.

The following specific example will serve to make this invention clear. The example describes a burning vessel wherein fluid coke from a hydrocarbon oil fluid coking process having a particle size in the range of about 40 to 800 microns is partially burned at a temperature of about 1125° F.

Example

Temperature, ° F.:

Vessel shell ----- 350

Internal ----- 1125

45 Pressure, p. s. i. g. ----- 12

Air rate @ 300° F., MM std. cu. ft./SD (dry) ----- 12.7

Coke rate to burner @ 950° F., tons/min. ----- 4.3

Coke burning rate, lbs./hr. ----- 3500

Coke hold up, tons ----- 21

Bed density, lbs./cu. ft. ----- 48

Gas velocity in bed, ft./sec. ----- 2.8

Internal vessel diameter, ft.:

Shell ----- 12.5

55 Vessel liner ----- 11.75

Grid diameter, ft. ----- 11.5

Grid thickness, inches ----- 0.5

Radius of curvature of grid, ft. ----- 25

Free area of grid, percent ----- 0.5

60 ΔP over grid, p. s. i.:

Normal ----- 5

Short time ----- 10

Total height of skirt, inches ----- 24

Height of vertical section in skirt, inches ----- 18

65 Skirt thickness, inches ----- 0.5

Skirt material ----- Carbon steel

Grid material ----- Carbon steel

Having described this invention, what is sought to be protected by Letters Patent is succinctly set forth in the following claims.

What is claimed is:

1. In an apparatus for contacting solids and gases at temperatures above about 900° F. which comprises a vertically disposed circular vessel, outlet means in the upper portion for removing gases, gas inlet means in

the bottom portion, a foraminous plate positioned within the lower portion of said vessel and adapted to support a bed of fluidized solids thereon, said plate being in horizontally spaced relationship to the walls of said vessel, and particle outlet means extending beneath said plate, the improvement which comprises employing a downwardly dished foraminous plate supported from above by an in-part vertically disposed, gas impervious, circular support, said support being attached to the walls of said vessel only in the region of the upper end of said support, said support being further characterized as extending downwardly for the major portion of its length and inwardly away from said vessel walls in spaced relation-

ship thereto, its lower end terminating at and encompassing said plate, whereby gas from beneath said plate is denied passage around the periphery of said plate, and the volume of reactor space below said plate and solids bed is reduced in amount.

2. The improvement of claim 1 wherein said circular support is at least in part insulated.
